UNITED STATES PATENT OFFICE.

LAFAYETTE D. LOUTHIAN, OF KENNEDALE, TEXAS.

MOTIVE POWER.

SPECIFICATION forming part of Letters Patent No. 367,307, dated July 26, 1887.

Application filed January 19, 1886. Serial No. 189,043. (No model.)

To all whom it may concern.

Be it known that I, LAFAYETTE D. LOUTHIAN, a citizen of the United States, residing at Kennedale, in the county of Tarrant, State of Texas, have invented certain new and useful Improvements in Motive Powers, of which the following is a specification, reference being had therein to the accompanying drawings.

10 This invention relates to certain new and useful improvements in motive powers, wherein the stroke of the actuating beam may be made more or less; and it is especially designed to be used in connection with pumps in shallow 15 wells, though it may of course be used for divers similar purposes.

In the accompanying drawings, forming a part of this specification, and on which similar letters indicate the same or corresponding 20 features, Figure 1 represents a side elevation of my improved motor as applied to a pump, a portion of the stock thereof being shown; Fig. 2, a side elevation of the rear portion of the frame, showing the apertures and the beam 25 dotted in and having corresponding apertures, and Fig. 3 a plan view of a guiding-block.

The letter A designates a suitable frame upon which is mounted the shaft B, provided with a drive-wheel, C, and mounted in journals D. Pivotal mounted in the rear of this 30 wheel is the slotted beam E, provided with a series of apertures, F, at one end, and at the other with a slot, G. At the end of the beam opposite the slot is a vertical plunger, H, 35 which has an up and down movement in the block I, which is suitably grooved for this purpose, the connection between the beam and the plunger being made by means of two links, one mounted on the end of the beam and the 40 other upon the plunger.

The letter J designates the shaft mounted on the frame near the plunger and provided with a small pulley, K, and having a crank, L, which slides within the slotted portion of 45 the beam, and is provided at its other end with a balance or fly wheel, M, so as to give a steady and uniform motion to the plunger when in operation.

The operation is as follows: Power being applied by means of the crank to the drive-wheel C, the pulley K, which is connected therewith by a belt, revolves and turns the shaft J. This, through the medium of the crank on said shaft, imparts an up and down movement to the beam E, which in turn gives the 55 same movement to the plunger.

It is to be observed that the beam E is provided with a series of holes near one end, and the frame is also provided with a corresponding series of apertures, so that by taking out 60 the pin which supports the beam and changing its position the throw of the beam may be regulated at pleasure.

Having thus fully described my invention, what I claim as new, and desire to secure by 65 Letters Patent, is—

1. The combination, with the frame and the rocking beam, of the block I, secured to said frame and grooved vertically, the plunger working in said groove, and the links S, one 70 secured to said plunger and the other to said beam and the two linked together, substantially as and for the purpose specified.

2. The improved motor described, consisting of the frame A, shaft B, journaled therein 75 and provided with a crank, as described, drive-wheel C on said shaft, shaft J, journaled in said frame parallel with the shaft B, pulley K on the shaft J, crossed belt connecting said pulley and drive-wheel, pivoted beam E, slotted 80 at one end, fly-wheel M on the shaft J, crank L, sliding within the slot in the said beam, the grooved block I, secured to the frame, the plunger working in the groove in said block, and the double-link connection S between said 85 beam and the plunger, all constructed, arranged, and operating substantially as shown and described.

In testimony whereof I affix my signature in presence of two witnesses.

LAFAYETTE D. LOUTHIAN.
